UNITED STATES PATENT OFFICE.

LINCOLN SCHROY, OF BROWNSVILLE, INDIANA.

ROPE-FORMING ATTACHMENT FOR BINDERS.

No. 862,590.

Specification of Letters Patent.

Patented Aug. 6, 1907.

Application filed December 18, 1905. Serial No. 292,385.

To all whom it may concern:

Be it known that I, LINCOLN SCHROY, a citizen of the United States, residing at Brownsville, in the county of Union, State of Indiana, have invented certain new 5 and useful Improvements in Rope-Forming Attachments for Binders; and I do hereby declare the following to be a full, clear, and exact description of the invention, such as will enable others skilled in the art to which it appertains to make and use the same.

10 This invention relates to rope forming attachments for binders and has for its object to provide an attachment for binders which may be readily applied to the same and which will form a continuous rope of straw for use in binding grain.

15 A further object of the invention is to provide a rope forming attachment which will be operated by the drawing of the straw through the same by the pressure rolls.

With the above and other objects in view, the invention 20 consists in the construction and arrangement of parts shown in the accompanying drawings in which:

Figure 1 is a top plan view of my invention, the cover for the same being partly broken away. Fig. 2 is a rear elevation of the same. Fig. 3 is a detail vertical 25 longitudinal sectional view through the attachment. Fig. 4 is an end elevation. Fig. 5 is a detail vertical transverse sectional view on the line 5—5 of Fig. 1. Fig. 6 is a similar view on the line 6—6 of Fig. 1. Fig. 7 is a detail view in elevation of one of the straw twisters, 30 and, Fig. 8 is a detail side elevation of the other of the straw twisters, the same being shown removed from its bearing blocks. Fig. 9 is a view in detail of one of the straw twisters.

Referring to the drawings, the numeral 10 denotes 35 the body of my attachment which comprises a pair of troughs 11 and 12, each including major and minor sides 13 and 14 and 15 and 16 respectively, the minor sides 14 and 16 being provided with flanges 17 and 18 respectively. The trough 11 is slidably mounted in 40 the trough 12 and has its flange 17 resting upon the upper face of a bar 19 which is secured to the underside of the flange 18 of the trough 12 and also to the binder (not shown) between the conveyer and the packer. Secured to the under side of the trough 12 at its other edge 45 is a bar 20 which extends laterally from the said trough and beneath the corresponding portion of the trough 11. Braces 21 have their ends secured between the bars 19 and 20 and the adjacent portions of the trough 12 and extend transversely of the said trough and beneath the same. Similar braces 22 are secured to the 50 upper face of the bars 19 and 20 and extend beneath the trough 11 in spaced relation to the same. Secured to the under side of the trough 11 adjacent its sides are guide

blocks 23 provided with flanges 24 which extend from their outer face to form grooves 25 between the said 55 flanges and the said trough and bars 26 are secured to the braces 22 and are provided with flanges 27 which extend from their faces adjacent the said trough and work in the grooves 25 in the bearing blocks 23.

A bearing bracket 28 is secured to the outer face of one 60 of the bars 26 and a similar bracket 29 is secured to the under side of a bar 30 which is connected at its ends to the braces 22 and mounted in the said bearing brackets 28 and 29 is a stem 31 which is provided at its outer end with a hand-wheel 32 and at its inner end with a pinion 65 33. The pinion 33 is in mesh with a rack-bar 34 which is secured to the under side of the trough 11 and extends longitudinally of the same.

From the foregoing, it will be seen that by rotating the stem 31 and consequently the pinion 33, the 70 trough 11 will be shifted longitudinally in the trough 12 and that by so shifting the said trough the attachment may be adjusted to accommodate different length of straw.

Mounted in the bottom of the trough 11 is a bearing 75 bracket 35 in which is mounted a shaft 36 carrying a feed roller 37. The bracket 35 includes laterally extending portions 38 and 39, one of which is provided with spaced pairs of lugs 39 for a purpose to be herein-after described. A second bearing bracket 40 is disposed upon the bearing bracket 35 and includes side members 41, end connecting portions 42 and lateral extensions 43 which rest upon the lateral extensions 38 and 39 of the bracket 35, one of the extended portions 43 being provided with oppositely extending lugs 44 85 which are engaged between the lugs of each pair of lugs 39. In the sides of the bracket 40 is journaled a shaft 45 upon which is mounted a feed roller 46, the said roller being disposed directly above the roller 37 and in spaced relation thereto. A bolt 47 is engaged in registering openings 48 in the extended portions 39 and 43 and has its lower end engaged through an opening 50 in the bottom of the trough 11. The lower portion of the bolt 47 is screw-threaded and is provided with a thumb-nut 51 between which and the under side of the 90 bracket 35 is engaged a helical spring 52, which when the thumb-nut 51 is tightened, exerts a pressure between the rollers 37 and 46 comprising substantially cylindrical bodies having ridges 53 formed upon their peripheries, the said 100 ridges extending from end to end of the said rollers. The end connecting portions 42 of the bearing bracket are provided with alining openings 54 for a purpose to be hereinafter described.

Mounted upon opposite ends of the shaft 36 and 45 are 105 bevel gears 55 and 56 respectively, the gear 55 being in

mesh with a bevel gear 57 mounted upon a shaft 58 which is in turn mounted in suitable bearing blocks 59 carried by the trough 11. Adjacent its opposite end to the bevel gear 57, the shaft 58 is provided with a pinion 59 which meshes with a gear 60 on the periphery of a straw twister 61, the said twister being mounted in a suitable bearing bracket 62.

The straw twister 61 comprises an annular body 62^a having laterally extending annular flanges 62^b, which is seated in an annular groove 62^c in the bracket 62. On its inner periphery, the annular body 62 of the straw twister 61 is provided with a series of straw twisting teeth 63. The gear portion 60 of the straw twister 61 is arranged to extend through slots 64 formed in its sides 15 of the bearing bracket 62. The gear 56 is in mesh with a bevel gear 64 mounted adjacent one end of a shaft 65, the said shaft being mounted at its extreme ends in suitable bearing brackets 66 carried by the trough 11. A gear 67 is secured to the shaft 66 which is in mesh with 20 a gear 68 forming a part of a straw twister 69. The straw-twister 69 comprises an annular body 70 which carries on its outer periphery the gear 68, the said gear extending in slots formed in the sides of a bearing bracket 71 and the annular body of the straw twister 25 being revolvably mounted in an annular groove 72 in the said bearing bracket. Arms 73 extend laterally from one side of the annular body of the straw-twister and are connected at their ends to diametrically opposite points on an annular member 75 which is provided with an annular flange 76 upon its periphery, the said flange 76 being engaged in an annular groove 77 formed in a bearing block or bracket 78 mounted in the trough 11 in rear of the bracket 71. The inner periphery of the annular body of the straw twister 69 is provided with a series of 30 straw twisting teeth 79 and extending forwardly upon the said annular body is a straw gatherer 80 which is in the form of a blade and is twisted in helical form and tapered toward its forward end which lies in a plane beyond the remainder of the gatherer.

40 Secured to the outer end of the trough 11 and outwardly of the bearing bracket 62 is a guide member 81 which comprises a pair of arms 82 which are held in spaced relation throughout their entire length by means of a block 83 through the medium of which the guide member is secured to the trough 11 and by means of a block 84 which is disposed intermediate the ends of the arms 82. The arms 82 extend upwardly and outwardly from the trough 11 for a short distance and are thence curved downwardly and rearwardly as at 85 and have 45 their free end portions extending beneath the said trough. Journalled between the arms 82 are rollers 86, one of the rollers being disposed at the point where the arms commence to curve downwardly, a second roller being disposed at substantially the middle of the bight 50 portion formed by bending the arms downwardly and rearwardly and the last of the rollers being mounted at the extreme free ends of the arms. One of the edges of the block 84 is recessed as shown at 87, the said recessed portion conforming to the contour of the periphery 55 of the adjacent roller. A yoke 88 has its bight portion 89 disposed below the roller located at the extreme free end of the guide member and has the ends of its spaced arms 90 turned inwardly toward each other as at 91 to 60 rotatably support the said roller between the arms 85.

A cover 92 is hinged as at 93 to the major side of the trough 11 adjacent its side edge and is provided at one of its ends with a downturned flange 94 and has its forward end portion curved downwardly as at 95.

In operation the straw as it passes from the conveyer to the packer, passes over the trough 12 and is engaged by the straw gatherer and fed to the straw twister. After the initial twisting action upon the straw it is engaged between the feed rollers 37 and 46 and through the openings in the end connection portions of the bearing bracket 40. The straw rope thus partly formed 75 is passed through the straw twister 61 and is given a final twisting after which it is passed over the guide rollers carried by the guide member 82 and under the said guide member and between the yoke 88 and its adjacent roller and thence to the packer. It will of 80 course be understood that the initial supply of straw must be passed through the attachment by hand and it will also be understood that the pulling action exerted by the packer will serve to draw the straw rope through the attachment as it is formed, the passage 85 of the rope between the feed roller serving to operate the twisters.

What is claimed is:

1. In a device of the character described, in combination, a straw gatherer, a twister, and means actuated by the passage of straw through said device for actuating said gatherer and said twister. 90
2. In a device of the character described, in combination, a gatherer, a plurality of twisters, and means actuated by the passage of straw through said device for actuating said gatherer and said twisters. 95
3. In a device of the character described, in combination, a twister, a gatherer associated with said twister, and means actuated by the passage of straw through said device for actuating said twister. 100
4. In a device of the character described, in combination, a twister, a gatherer carried by said twister, and means actuated by the passage of straw through said device for actuating said twister. 105
5. In a device of the character described, in combination, a plurality of twisters, a gatherer carried by one of said twisters, and means actuated by the passage of straw through said device for actuating said twisters. 110
6. In a device of the character described, in combination, a twister, a gatherer, means actuated by the passage of straw through said device for actuating said twister and said gatherer, and means for guiding the rope formed by said device after its passage therefrom. 115
7. In a device of the character described, in combination, a gatherer, a twister and adjustable means actuated by the passage of straw through said device for actuating said gatherer and said twister. 120
8. In a device of the character described, a twister, a gatherer carried by said twister and rollers arranged for the passage of straw therebetween after its passage through said twister, and means actuated by the passage between said rollers for actuating said twisters and said gatherer. 125
9. In a device of the character described, a twister, a gatherer carried by said twister, rollers arranged for the passage of straw therebetween after its passage from the said twister, means actuated by the passage of said straw between said rollers for actuating said twister and said gatherer, and means for adjusting said rollers. 130
10. In a device of the character described, a twister, a gatherer carried by said twister, rollers arranged for the passage of straw therebetween after its passage from the said twister, means actuated by the passage of said straw between said rollers for actuating said twister and said gatherer, and means for adjusting the pressure of said 135 rollers.

11. A device of the character described comprising troughs, a gatherer and a twister mechanism carried by one of said troughs, and means for adjusting said trough with respect to the other of said troughs.
- 5 12. In a device of the character described in combination, a pair of troughs, a gatherer and a twister mechanism carried by one of said troughs, and means for adjusting said troughs longitudinally of each other.
13. In a device of the character described, the combination
- 10 with a trough, of a twister, a gatherer, and means actuated by the passage of straw through said trough for actuating said twister and said gatherer.
14. In a device of the character described, in combination, a gatherer, a twister, rollers arranged for the passage of straw therebetween and means associated with said rollers and said gatherer and said twister for actuating the latter when the former is actuated by the passage of straw. 15
- In testimony whereof, I affix my signature, in presence of two witnesses.

LINCOLN SCHROY.
